UNITED STATES PATENT OFFICE.

HERMAN T. CHISHOLM, OF BALTIMORE, MARYLAND, ASSIGNOR OF ONE-HALF TO
WALTER F. KILCHENSTEIN, OF BALTIMORE, MARYLAND.

GAME-TABLE.

1,142,305.

Specification of Letters Patent.

Patented June 8, 1915.

Application filed September 4, 1914. Serial No. 360,240.

To all whom it may concern:

Be it known that I, HERMAN T. CHISHOLM, a citizen of the United States, residing at Baltimore, State of Maryland, have invented 5 certain new and useful Improvements in Game-Tables; and I do hereby declare the following to be a full, clear, and exact description of the invention, such as will enable others skilled in the art to which it applies 10 pertains to make and use the same.

This invention relates to game tables and the primary object of the invention is the provision of a game table upon which an interesting and pleasure giving game may be 15 played.

Another object of this invention is the provision of a game table which is provided with a channel and a deflecting member for deflecting pool balls therefrom at various 20 acute angles for depositing into pockets for registering the game.

With the foregoing and other objects in view this invention consists in such novel features of construction, combination and 25 arrangement of parts as will be hereinafter more fully described, illustrated in the accompanying drawings and claimed.

In describing the invention in detail reference will be had to the accompanying 30 drawing wherein like characters designate like or corresponding parts throughout the several views, and in which:—

Figure 1 is a top plan view of the improved table. Fig. 2 is a side elevation of 35 the table. Fig. 3 is a longitudinal, sectional view through the table. Fig. 4 is a cross sectional view on the line 4—4 of Fig. 1. Fig. 5 is a cross sectional view on the line 5—5 of Fig. 1, and Fig. 6 is a detail 40 perspective view of a part of the game board.

Referring more particularly to the drawings, 1 designates a supporting base board which may be mounted upon any suitable type of legs (not shown) which has secured 45 to its upper surface centrally thereon a second board or block 2, which has billiard cloth mounted upon its upper surface as at 3. The board 1 also has mounted upon its upper surface about its marginal edge moldings 5 which are spaced from the edges of the block 2, leaving a channel 6 surrounding the block 2, which channel is of greater width at the ends of the block than along the sides as is clearly shown in Fig. 1 of the drawing. The block 2 has pins 7 and 8

adjustably secured along one side edge thereof of about which pins is stretched an elastic member 9. The pins 7 and 8 are provided with sharpened points so that they may be driven into the block 3 at different positions 60 along the length or transversely of the block to provide for adjusting the elastic member 9 with respect to the arcuate wall 16 and with respect to the block 20. If it is so desired the block 3 may be provided with a 65 plurality of spaced openings 8' as shown in Fig. 1 of the drawings, and ordinary stub ends 10 may be used and positioned in various of the openings 8' for the adjustable positioning of the elastic member 9 with respect to the arcuate ball guiding wall 16. The elastic member 9 projects upwardly 70 from the upper surface of the block 2 and its function will be hereinafter more fully described.

The portion of the channel 6 which is positioned at the end of the block adjacently to the elastic member 9 has a block 11 inserted therein, which block has its rear ends 75 arcuate in shape and its forward ends substantially straight, the block forming substantially a semi-circle. An approach 12 is formed integrally with the straight edge of the block 11 at one end thereof and it extends into the side channel 13, extending 80 upwardly from the base of the channel 13 to the upper surface of the block 11 forming an incline of the approach therefor. An ear or transversely extending projection 14 is formed upon the straight edge of the block 13 at the opposite end thereof to the approach 12 and it extends into the channel 15, 85 formed on the opposite side edge of the block 2 from the channel 13.

A guiding wall 16 is secured to the rear 90 arcuate edge of the block 14 and it projects upwardly therefrom. The guiding wall 16 tapers upwardly from the point 17, or the line of conjunction between the approach 12 and the straight edge of the block 11 to 95 the point 18 which is substantially one-third of the entire distance or length of the arcuate wall, from which point it is tapered downwardly merging into the surface line of the block 11 at the terminus of the extension 14. The outer edge of the extension 14 is arcuate so that the portion of the guiding wall 16 which is mounted thereupon will extend to the edge of the block 2 extending 100 diagonally across the channel 15.

The channel 15 has a block 20 slidably mounted therein, which block has a plurality of pockets 21 formed in longitudinal spaced relation in the upper surface thereof.

5 The upper surface of the block 20 alines with the upper surface of the block 2 and it is mounted longitudinally within the slot 15 for various positioning along the length of the side of the block 2.

10 The molding 5 which extends around the marginal edges of the base board 1 has billiard cloth secured to its upper surface as is shown at 23 and this molding has its upper edge cut at an incline extending downwardly

15 toward the board 1 and inwardly toward the block 2, the inner edge of the inclined portion being positioned a short distance below the upper surface of the block 2 as is clearly shown in Fig. 4 of the drawings.

20 In playing a game upon the improved board heretofore described, ordinary billiard balls and cues are employed and the billiard balls are placed in the channel 13 in the position indicated in dotted lines and shown as 25 in Fig. 1 of the drawings. The ball is then propelled, by means of striking it with the cue forwardly along the channel 13 and upwardly over the approach 12, and its momentum causes it to travel about the arcuate 30 wall 16 roll therefrom and engage the flexible member 9, which flexible member deflects or forces the billiard ball therefrom at an acute angle to the direction of travel of the ball prior to the striking of the elastic 35 member, the game is to shoot the billiard balls and cause them to be seated in the various pockets 21 formed in the block 20.

From the foregoing description taken in connection with the accompanying drawings

40 the advantages of the construction and of the method of operation of the improved game table will be readily apparent to those skilled in the art to which this invention appertains and, while in the foregoing description, the principle of the operation of this invention has been described together with various features of construction, it is to be understood that certain minor features of construction, combination and arrangement 45 of parts may be altered to suit practical conditions provided such alterations are comprehended within the scope of what is claimed.

What is claimed is:—

55 1. In a game board, a supporting base board, a block mounted centrally in said base board, a molding extending upon the marginal edge of said board and being spaced from said block for forming channels between said block and the inner faces 60 of said molding, a block positioned in one of said channels, a tapered approach formed integral with said block and projecting into another of said channels, and an arcuate ball 65 guiding wall carried by said block.

2. In a game board, a supporting base board, a block mounted centrally in said base board, a molding extending upon the marginal edge of said board and being spaced from said block for forming channels between said block and the inner faces 70 of said molding, a block positioned in one of said channels, a tapered approach formed integral with said block and projecting into another of said channels, an arcuate ball 75 guiding wall carried by said block, a block slidably mounted within another of said channels and being provided with a plurality of facial pockets.

3. In a game board, a supporting base board, a block mounted centrally in said base board, a molding extending upon the marginal edge of said board and being spaced from said block for forming channels between said block and the inner faces 80 of said molding, a block positioned in one of said channels, a tapered approach formed integral with said block and projecting into another of said channels, a block mounted in one of said channels and being provided with a plurality of facial pockets, and an arcuate ball guiding wall carried by said block, 85 an elastic member supported by and upstanding from said first named block for receiving balls from said arcuate guiding 90 wall and deflecting them into said pockets.

4. In a game board, a supporting base board, an arcuate ball guiding wall carried by one end of said board, a block slidably carried by said base board and being provided with a plurality of facial pockets, and an elastic member supported by and upstanding from said base board for receiving balls from said arcuate guiding wall and deflecting them into said pockets. 105

5. In a game board structure, a game board having a plurality of upstanding pins detachably secured thereto, an elastic ball deflecting member detachably mounted upon said pins, and a block provided with a plurality of facial pockets slidably carried by said game board and adjustable with respect to said elastic member.

6. In a game board structure, a game board, a ball guiding wall carried by one end of said game board, a block slidably carried by said game board, said slideable block being provided with facial recesses and slideable along said game board for adjustment with respect to said guiding wall. 115

7. In a game board structure, a game board, an arcuate ball guiding wall carried by one end of said game board, a block slidably carried by said game board, said slideable block being provided with facial recesses and slideable along said game board for adjustment with respect to said guiding wall, and an upstanding elastic member carried by said board oppositely of said block for receiving balls from said arcuate 125 130 wall.

guiding wall and deflecting them into said pockets.

8. In a game board structure, a game board being provided with a facial pocket, 5 an upstanding ball guiding wall carried by one end of said board, an elastic member carried by and upstanding from said game board, said pocket and said elastic member being adjustable with respect to each other 10 and said guiding wall.

9. In a game board structure, a supporting base board, a block mounted centrally upon said base board, a molding extending about the marginal edge of said board and 15 being spaced from said block for forming channels between said blocks and the inner faces of said molding, a block positioned in one of said channels, a tapered approach formed integrally with said block and projecting 20 into another of said channels, an arcuate ball guiding wall carried by said block, a block slidably mounted in one of said channels and being provided with facial pockets, an elastic member supported by and 25 upstanding from said first named block for receiving balls from said arcuate guiding wall and deflecting them into said pockets, said elastic member and said slidable block being adjustable with respect to each other 30 and said arcuate guiding wall.

10. In a game board structure, a base board, a block mounted centrally upon the upper face of said board, a molding extending about the marginal edge of said base 35 board and being spaced from said block for forming channels between said block and the inner faces of said molding, an upstanding ball guiding wall carried by one end of said base board, a block slidably mounted in one 40 of said channels at one side of said first named block and an upstanding elastic member carried by said block upon the opposite side of said slidable block.

11. In a game board structure, a base 45 board, a block mounted centrally upon the upper face of said board, a molding upon the marginal edge of said base board and being spaced from said block for forming channels between said block and the inner 50 faces of said molding, an upstanding ball guiding wall carried by one end of said base board, a block slidably mounted in one of the channels at one side of said first named block, and an upstanding elastic member 55 carried by said block upon the side opposite of said slidable block, said elastic member being adjustable with respect to said guiding wall, and to said sliding block.

12. In a game board structure, a base 60 board, a block mounted centrally upon the face of said board, a molding extending upon the marginal edge of said base board and being spaced from said block for form-

ing channels between said block and the inner faces of said molding, an upstanding 65 ball guiding wall carried by one end of said base board, a block slidably mounted in one of said channels at one side of said first named block, and an upstanding elastic member carried by said block upon the side 70 opposite of said slidable block, said elastic member being adjustable with respect to said guiding wall and said sliding block, said sliding block being provided with a facial pocket and adjustable with respect to 75 said guiding wall and said elastic member.

13. In a game board structure, a supporting base board, a block mounted centrally upon the upper surface of said base board, a molding extending upon the marginal edge 80 of said board and being spaced from said block for forming channels between said block and the inner faces of said molding, a block positioned in one of said channels, a tapered approach formed integrally with 85 said block and projecting into another of said channels, an arcuate ball guiding wall carried by said block, a block provided with facial pockets slidably mounted in one of said channels at one side of said first named 90 block, an upstanding elastic member carried by said block upon the side opposite of said slidable block, said elastic member being adjustable with respect to said guiding wall and said slidable block and said sliding 95 block being adjustable with respect to said guiding wall and said elastic member.

14. In a game board structure, a supporting base board, a block mounted centrally upon the upper surface of said base board, a molding extending upon the marginal edge of said base board and being spaced from said block for forming channels between said blocks and the inner faces of 100 said molding, a block positioned in one of the channels, a tapered approach formed integrally with said block and projecting into another of said channels, an arcuate ball guiding wall carried by said block, a block being provided with a plurality of 110 facial pockets slidably mounted in another of said channels and adjustable with respect to said guiding wall, a plurality of detachable pins secured to and upstanding from said first named centrally disposed block, and an elastic member detachably mounted upon said pins for receiving balls from said arcuate guiding wall and deflecting them 115 into said pockets.

In testimony whereof I affix my signature 120 in presence of two witnesses.

HERMAN T. CHISHOLM.
